UNITED STATES PATENT OFFICE.

ARTHUR O. DUPUY, OF CLEVELAND, OHIO, ASSIGNEE OF ONE-HALF TO ERNEST W. FARR, OF CLEVELAND, OHIO.

CABLE, CHAIN, OR ANALOGOUS DRIVE.

Specification of Letters Patent. Patented Nov. 2, 1920.

1,357,316.

Application filed February 26, 1918. Serial No. 219,279.

To all whom it may concern:

Be it known that I, ARTHUR O. DUPUY, a citizen of the United States, resident of Cleveland, county of Cuyahoga, and State 5 of Ohio, have invented new and useful Improvements in Cable, Chain, or Analogous Drives, of which the following is a specification, the principle of the invention being herein explained and the best mode in 10 which I have contemplated applying that principle, so as to distinguish it from other inventions.

My invention relates to driving mechanism and particularly to driving means involving a pair of sheaves or sprocket-wheels or analogous driving members disposed in relatively oblique positions. Particularly, my invention is designed for use 15 in connection with the pallet-conveying mechanism of brick making plants shown and described in my pending application and for U. S. Letters Patent, Serial No. 219,278. It is designed to so arrange and actuate a pair of driving sheaves or sprocket-wheels 20 that the top strands of a pair of endless ropes or chains driven by said wheels travel a certain distance apart and the lower strands thereof travel intermediate said top strands and a less distance apart.

30 The annexed drawings and the following description set forth in detail certain means embodying my invention, the disclosed means, however, constituting but one of various mechanical forms in which the principle of the invention may be employed.

In said annexed drawings:

Figure 1 represents a partial side elevation and partial axial vertical section of my improved driving mechanism; Fig. 2 represents a front elevation thereof; Fig. 3 represents a section of a detail, taken in the plane indicated by the line III-III, Fig. 4; Fig. 4 represents an elevation of one of the driving sheaves; Fig. 5 represents a vertical axial section, taken in the plane indicated by the line V-V, Fig. 4; Fig. 6 represents a plan view of the mechanism; Fig. 7 represents a suggestion of an inside elevation of one of the driving sheaves, illustrating different positions assumed by the automatically adaptable means connecting said sheaves and the main driving member; Fig. 8 represents an elevation of one side of the mechanism, shown for the purpose of illustrating further the adaptability 55 shown in Fig. 7.

Referring to the annexed drawings, a main driving shaft 1 is shown, the same being driven by any suitable source of power (not shown). Loosely mounted upon 60 said shaft 1 is a pinion 2 which is adapted by a suitable clutch mechanism to be thrown into rotative engagement with said shaft and to actuate a gear 3 provided with the enlarged arm portions 3², a certain use for 65 which will be hereinafter fully explained. Said gear 3 is rotatably mounted upon a journal member 4 supported in a manner hereinafter fully explained. Secured to a main supporting frame 6 and upon either 70 side thereof are a pair of brackets 5 disposed in the generally oblique relative positions plainly shown in Fig. 1. A pair of inwardly projecting members provided with journal surfaces 7 are secured in said brackets 5 by means of the screws 8 and key 75 and key-ways 9. The inner ends of said journal members 7 are supported in a pair of bevel collars 10, which collars are disposed intermediately the hub members 13' 80 of a pair of sheaves 13, hereinafter more fully described, and the outer surfaces of the hub member of the gear 3. The inner ends 7' of said journal members 7 are beveled, as plainly indicated in Fig. 1, and 85 disposed between said inner surfaces 7' and supported and alined by means of keys and key-ways 11 and screws 12 in the bevel collars 10 is the journal member 4, hereinbefore mentioned, upon which the gear 3 90 rotates. Disposed upon the journals 7, thus obliquely supported relatively to each other, are a pair of sheaves 13 provided with the hub portions 13' and with enlarged portions 13², Figs. 3 and 4, hereinafter more 95 fully described, each formed with a hole 13³ and a slot 13² intersecting said hole. Alternate arms 3' of the gear 3 are provided with enlarged portions 3², as plainly shown in Fig. 1, within which portions 3² bars 14 are 100 symmetrically secured, there being three of said bars, as is plainly indicated in Fig. 7. Connected to the outer ends of each of said bars 14 are a pair of links 15 of the general design shown plainly in Figs. 7 and 105 8, said links 15 being provided with enlarged holes intersected by the bars 14 and retained upon said bars by intersecting pins

17. The other ends of the links 15 intersect the slots 13² of the sheaves 13 hereinbefore mentioned and are retained therein by pins 15' disposed within the holes 13³ and there-
5 in retained by the pins 16, all as plainly shown in Fig. 3, the holes of the links 15 through which said pins 15' are inserted being enlarged.

It is evident from the foregoing description that the actuation of the driving shaft 1 will rotate the gear 3 through the pinion 2, which action will rotate the bars 14 and consequently the links 15, resulting in the rotation of the pair of sheaves 13 in the oblique relation shown in Fig. 1. This action results in the driving of a pair of endless cables a certain distance apart in one direction and a lesser distance apart in the other direction and above or below the horizontal position assumed in the first-mentioned direction. As plainly shown in Figs. 7 and 8, the enlarged holes provided in both ends of the links 15 intersected by the bars 14 and the connecting pins 15', respectively, provide for the necessary changes in the effective lengths and relative positions of the links 15 produced during the rotation by the relative obliquity of the sheaves 13 to the gear 3.

30 It is apparent that the sheaves 13 may be driven by means other than the specific driving means hereinbefore described and shown in the accompanying drawings, such as bevel gears, worms, etc. Furthermore, 35 flexible members connecting the driving member 3 and the pair of sheaves 13 could be utilized instead of rigid automatically adaptable links as shown. Such flexible members could be chains or ropes or other 40 suitable members. It is further evident that the pair of driving wheels 13 might be chain sprockets or analogous driving means instead of rope sheaves.

What I claim is:

45 1. In a cable, chain or analogous drive, the combination of a support; a pair of driving wheel rotatably mounted thereon and disposed obliquely relatively to each other; primary driving means; and means connecting the latter and said driving wheels and arranged to have varying effective lengths.

50 2. In a cable, chain or analogous drive, the combination of a support; a pair of driving wheels rotatably mounted thereon and disposed obliquely relatively to each other; primary driving means; and means connecting the latter and said driving wheels and arranged automatically to have varying effective lengths during the rotation of said wheels.

55 3. In a cable, chain or analogous drive, the combination of a driving shaft; a pair of driving wheels disposed obliquely relatively to each other; and means connected

to said driving shaft and said wheels, respectively, arranged to have varying effective lengths, and adapted to drive said wheels from said shaft.

4. In a cable, chain or analogous drive, 70 the combination of a driving shaft; a pair of driving wheels disposed obliquely relatively to each other; and means connected to said driving shaft and said wheels, respectively, and adapted positively to drive the 75 latter from said shaft, said means being arranged automatically to vary its effective length during the rotation of said wheels.

5. In a cable, chain or analogous drive, 80 the combination of a support; a pair of driving wheels rotatably mounted thereon and disposed obliquely relatively to each other; primary driving means; and means connecting the latter and said driving wheels and arranged automatically to have 85 constantly varying effective lengths during the rotation of said wheels.

6. In a cable, chain or analogous drive, 90 the combination of a driving shaft; a pair of driving wheels disposed obliquely relatively to each other; means for supporting said wheels; a driving member mounted to rotate intermediate of, and symmetrically relatively to, said wheels and actuated by said driving shaft, said member being supported by said wheel-supporting means; 95 and members connecting said driving member and said wheels to effect the rotation of the latter and arranged to have varying effective lengths.

100 7. In a cable, chain or analogous drive, the combination of a driving shaft; a pair of driving wheels disposed obliquely relatively to each other; means for supporting said wheels; a driving member mounted to 105 rotate intermediate of, and symmetrically relatively to, said wheels and actuated by said driving shaft, said member being supported by said wheel-supporting means; and members connecting said driving member 110 and said wheels to effect the rotation of the latter, said members being so connected as automatically to vary their effective lengths during the rotation of said wheels.

115 8. In a cable, chain or analogous drive, the combination of a driving shaft; a pair of driving wheels disposed obliquely relatively to each other; means for supporting said wheels; a driving member mounted to 120 rotate intermediate of, and symmetrically relatively to, said wheels and actuated by said driving shaft, said member being supported by said wheel-supporting means; members rigidly secured to said driving member; and members secured to said 125 driving member; and members secured to said wheels and also secured to said rigid members and arranged to have constantly varying effective lengths during the rotation of said wheels.

130 9. In a cable, chain or analogous drive,

the combination of a driving shaft; a pair of driving wheels disposed obliquely relatively to each other; a driving member actuated by said driving shaft and mounted to rotate intermediate of said wheels; and automatically adjustable means secured to said driving member and said wheels.

10. In a cable, chain or analogous drive, the combination of a driving shaft; a main supporting member; a pair of journals supported upon the latter whose axes lie relatively obliquely in the same vertical plane, said journals being formed with beveled inner ends; a third journal disposed and supported between the inner ends of said pair of journals, the construction being such that the axis of said last-mentioned journal lies in a horizontal plane and symmetrically relatively to said aforementioned axes; a pair of driving wheels rotatably mounted upon said pair of journals; a driving member rotatably mounted upon said third journal and actuated by said driving shaft; and means arranged to have varying effective lengths and connecting said driving member and said wheels to rotate the latter.

11. In a cable, chain or analogous drive,

the combination of a support; a pair of journals mounted thereon whose axes lie relatively obliquely; a third journal suitably supported intermediate said pair of journals; a pair of driving wheels rotatably mounted upon said pair of journals; a driving member rotatably mounted upon said third journal; primary driving means; 30 means adapted to rotate said driving member from said primary driving means; and means connecting said driving member and said wheels to rotate the latter.

12. In a cable, chain or analogous drive, 40 the combination of a driving shaft; a main supporting member; a pair of journals supported upon the latter, whose axes lie relatively obliquely; a third journal supported by and between said pair of journals; a pair 45 of driving wheels rotatably mounted upon said pair of journals; a driving member rotatably mounted upon said third journal and actuated by said driving shaft; and means connecting said driving member and 50 said wheels to rotate the latter.

Signed by me, this 9th day of February,
1918.

ARTHUR O. DUPUY.
